UNITED STATES PATENT OFFICE.

FRANK H. ILSE, OF DETROIT, MICHIGAN.

FASTENER FOR VEHICLE-CURTAINS.

1,169,542.

Specification of Letters Patent. Patented Jan. 25, 1916.

Application filed October 31, 1914. Serial No. 869,568.

To all whom it may concern:

Be it known that I, FRANK H. ILSE, a citizen of the United States of America, residing at Detroit, in the county of Wayne

5 and State of Michigan, have invented certain new and useful Improvements in Fasteners for Vehicle-Curtains, of which the following is a specification, reference being had therein to the accompanying drawings.

10 The invention relates to side curtains for vehicles and it is the object of the invention to provide means operable from the inside for securing the lower edge of the curtains to the outside of the vehicle body. Usually 15 such curtains are secured by turn-buttons on the body engaging eyelets in the curtain, but these can only be operated from the outside. With my improved construction, means are provided for engaging the eyelets 20 with outwardly-extending buttons and locking the same, said means being readily operable from within the vehicle.

In the drawings: Figure 1 is a perspective view of a vehicle canopy provided with curtains having my improved attachment device; Fig. 2 is a cross section through the attachment device; Fig. 3 is a perspective view showing the attachment device in locked position; and Fig. 4 is a similar view 30 showing it in unlocked position.

A is the vehicle body, B is a side curtain, the lower edge of which overlaps the side of the body, and C is the stud or button projecting outward from the body and with 35 which the curtain is engaged. To permit of engaging the eyelet of the curtain with the stud C I have provided an attachment device, comprising a member D preferably formed of sheet metal, which is riveted or 40 otherwise secured to the inside of the curtain and is provided with an aperture E for engaging the stud.

F is a member slidably engaging the member D having an aperture G for registration 45 with the aperture E to receive the head of the stud C. The aperture G is formed with a portion G' which is contracted in width for engagement with the shank of the button so as to interlock with the head thereof.

50 H is a spring engaging the members D and F and holding them normally in position where the entrance apertures are out of exact registration. Thus by relatively adjusting these members F and D against 55 the tension of the spring their entrance apertures may be registered so as to permit

engagement with the stud, while upon releasing said members the spring will throw them out of registration, causing an interlock with the stud. 60

To permit of operating the members F and D from inside the vehicle said members are provided with upward extensions F' and D', which are parallel with the inner face of the curtain and rise above the top of the 65 body A. The arrangement is such that the two upward extensions may be grasped between the thumb and finger of the operator and may be relatively moved to register their entrance apertures, and at the same 70 time said members may be moved as a unit to disengage or engage the same with the stud. The relative movement of the members is facilitated by roughing the surface thereof as indicated at J. 75

With the construction as described, the curtains may be readily attached or detached from the stud C and when attached will be securely locked against accidental displacement. 80

What I claim as my invention is:—

1. In a fastener for securing a curtain to a member overlapped by said curtain, the combination with a button or stud adapted to be mounted upon said member, of a locking eyelet adapted to be interiorly attached to the overlapping portion of the curtain, and comprising relatively movable parts having registrable apertures for engaging the stud, and respectively having portions 85 adapted to extend beyond an edge of said member, forming finger grasps, for displacing said parts oppositely to register said apertures and allow disengagement of the eyelet from the stud. 95

2. In a fastener for securing a curtain to a member overlapped by said curtain, the combination with a button or stud adapted 100 to be mounted upon said member, of a locking eyelet adapted to be interiorly attached to the overlapping portion of the curtain and comprising relatively movable parts, respectively having apertures, normally imperfectly registered, to engage a reduced portion of the stud, and respectively having 105 projecting adjacent parallel portions adapted to similarly extend beyond an edge of said member, forming finger grasps for displacing said parts oppositely to register said apertures and allow disengagement of the 110 eyelet from the stud.

3. In a fastener for securing a curtain to

a member overlapped by the curtain, the combination with a button or stud adapted to be mounted upon said member, of a locking eyelet adapted to be carried by the curtain, comprising two relatively movable parts, one of which is adapted to be secured to the curtain and forms ways in which the other is mounted to slide, said parts being formed with apertures to engage said stud, 5 normally imperfectly registered, a pin mounted upon the sliding part, and a spring mounted upon said pin having its ends bearing upon corresponding edge portions of the other part tending to maintain the two parts 10 in their normal relation.

4. In a fastener for securing a curtain to a member overlapped by said curtain, the combination with a button or stud adapted to be mounted upon said member, of a locking eyelet adapted to be carried by the curtain primarily comprising two relatively movable parts having apertures for engagement with said stud, normally imperfectly registered, and having finger grasps for accomplishing a relative motion of said parts, 20 one of the parts being formed with ways in which the other part slides, one of the parts being formed with a stop, encountering the other part when the two said apertures register. 25

5. In a fastener for securing a curtain to a member overlapped by the curtain, the combination with a button or stud adapted to be mounted upon said member, of a locking eyelet adapted to be carried by the curtain, comprising relatively movable parts having apertures for engagement with said stud, normally imperfectly registered, said parts being formed with parallel and adjacent 35 finger grasps for relatively moving said members into complete registration or moving the same as a unit into or out of engagement with the stud.

6. In a fastener for securing a curtain to 40 a member overlapped by the curtain, the

combination with a button or stud, adapted to be mounted upon said member, of a locking eyelet adapted to be carried by the curtain, comprising two relatively movable parts, one of which comprises an intermediate portion and lugs oppositely projecting from said portion for engagement with the curtain, and the other part being mounted in slideways formed at the junctures of said lugs with said intermediate portion, the two 50 55 said parts being formed with registrable apertures to engage the stud.

7. In a fastener for securing a curtain to a member overlapped by the curtain, a securing button or stud adapted to be mounted upon said member, and a locking eyelet adapted to be interiorly secured to the curtain, comprising relatively movable members, one slidably engaged by the other, said parts having apertures for engagement with 60 65 said stud, a spring normally maintaining a relative position of said parts resulting in imperfect registration of said apertures, and parallel adjacent extensions from said members, forming finger grasps for relatively 70 moving said members into registration and for moving the same as a unit into or out of engagement with the stud.

8. In a fastener for securing a curtain to a member overlapped by said curtain, the combination with a button or stud adapted to be mounted upon said member, of a locking eyelet adapted to be interiorly attached to the overlapping portion of the curtain, comprising relatively movable parts coöoperating to engage the stud and respectively having portions adapted to extend beyond an edge of said member forming finger grasps for actuating relative displacement of said parts. 75 80

In testimony whereof I affix my signature 85 in presence of two witnesses.

FRANK H. ILSE.
